OTHER PUBLICATIONS

Rainer, Michael D.; Design U.S. Appl. No. 29/653,799, entitled Miniature Inline Sensing Device for Continuous Measurement of Fluid Properties, filed Jun. 19, 2018; in its entirety.

Primary Examiner — Antoine Duval Davis

(74) *Attorney, Agent, or Firm* — Ulmer & Berne LLP

(57) **CLAIM**

The ornamental design for a device with integrated sensor for incorporation into fluid measurement system, as shown and described.

DESCRIPTION

FIG. 1 is a front top perspective view of the device with integrated sensor for incorporation into fluid measurement system;

FIG. 2 is a front elevational view of the device with integrated sensor for incorporation into fluid measurement system of FIG. 1;

FIG. 3 is a rear elevational view of the device with integrated sensor for incorporation into fluid measurement system of FIG. 1;

FIG. 4 is a right side elevational view of the device with integrated sensor for incorporation into fluid measurement system of FIG. 1;

FIG. 5 is a left side elevational view of the device with integrated sensor for incorporation into fluid measurement system of FIG. 1;

FIG. 6 is a top plan view of the device with integrated sensor for incorporation into fluid measurement system of FIG. 1;

FIG. 7 is a bottom plan view of the device with integrated sensor for incorporation into fluid measurement system of FIG. 1; and,

FIG. 8 is a rear bottom perspective view of the device with integrated sensor for incorporation into fluid measurement system of FIG. 1.

The broken-line disclosure of elements is understood to represent portions of the article in which the design is embodied, but which form no part of the claimed design.

1 Claim, 7 Drawing Sheets
